Patented May 3, 1966

204,610

CAROM GOLF GAME BOARD

Darwin D. Williams, 5850 19th Ave., and Chad R.
Carter, 5800 62nd St., both of Sacramento, Calif.

Filed June 28, 1965, Ser. No. 85,935

Term of patent 14 years

(Cl. D34—5)

FIG. 2

FIG. 3

FIG. 4

FIGURE 1 is a rear perspective view of a carom golf game board, showing our new design;

FIGURE 2 is a top plan view;

FIGURE 3 is an elevational view of one side; and,

FIGURE 4 is a front elevational view thereof.

The dominant features of our new design reside in the full line portions shown.

We claim:

The ornamental design for a carom golf game board, as shown and described.
